UNITED STATES PATENT OFFICE.

CHARLES S. SHARP, OF AUBURN, NEW YORK, ASSIGNOR TO THE D. M. OSBORNE & COMPANY, OF SAME PLACE.

DESIGN FOR A HARROW-FRAME.

SPECIFICATION forming part of Design No. 28,814, dated June 7, 1898.

Application filed July 3, 1897. Serial No. 643,460. Term of patent 14 years.

To all whom it may concern:

Be it known that I, CHARLES S. SHARP, a citizen of the United States, residing at Auburn, in the county of Cayuga and State of New York, have invented and produced a new and original Design for a Harrow-Frame, of which the following is a specification, reference being had to the accompanying drawings, forming a part thereof.

Figure 1 is a plan view of a harrow-frame, showing my new design. Fig. 2 is a side view of the harrow-frame shown in Fig. 1.

As shown in the drawings, the leading or material features of my design consist in a rectangular frame a^2 open at one end, extensions a^3 from the free ends of said frame,

transverse shaft a^4 , connecting said extensions, and transverse bars a^5 and a^6 , extending across the frame, below the level thereof, and in front of shaft a^4 , said bars a^5 being in front of bar a^6 .

I claim—

The design for a harrow-frame as herein shown and described.

In testimony whereof I have signed my name to this specification in the presence of two subscribing witnesses.

CHARLES S. SHARP.
